UNITED STATES PATENT OFFICE.

MARTIN BETZLE, OF PRAIRIE DU CHIEN, WISCONSIN.

ROTARY ENGINE.

1,220,594.

Specification of Letters Patent. Patented Mar. 27, 1917.

Application filed October 15, 1915. Serial No. 56,051.

To all whom it may concern:

Be it known that I, MARTIN BETZLE, a citizen of Germany, residing at Prairie du Chien, in the county of Crawford, in the 5 State of Wisconsin, have invented certain new and useful Improvements in Rotary Engines, of which the following is a specification.

My present invention relates to improvements in the art embracing internal combustion engines, and more particularly to a specific type of rotary motor which can be operated at an abnormally high speed and which will develop a maximum degree 15 of power and efficiency.

The object of my present invention is to provide such a motor, extremely simple in construction and of few parts, and one that will run smoothly, and in which friction is reduced to a minimum.

Another object resides in the provision of a rotor journaled within a water-jacket, said rotor being of smaller diameter than the jacket and disposed therein similar to 25 a rotatable spool. A disk or fin integral with the water-jacket extends intermediate the two flanges of the rotor, and serves to divide the same into cylinders.

Having these and other objects of general 30 utility and design in view, I have illustrated a preferred embodiment of my invention in the accompanying drawings, in which—

Figure 1 is a cross sectional view on line 35 1—1 of Fig. 4.

Fig. 2 is a view at right angles to Fig. 1.

Fig. 3 is a fragmentary section showing the arrangement of the intake ports.

Fig. 4 is a transverse section on line 4—4 40 of Fig. 1.

Fig. 5 is a view of the rotor disassembled from the casing of the motor.

Fig. 6 is a schematic view showing the relative arrangement of the valves.

Fig. 7 is a similar view the valves being in their extreme outer position from that as shown in Fig. 6.

Fig. 8 is an enlarged fragmentary detail elevation of one of the abutments, and

Fig. 9 is a transverse section therethrough on line 9—9.

Similar reference characters refer respectively to similar parts throughout the several views.

55 My invention consists in providing a substantially cylindrical water-jacket 10, which

is mounted upon the usual base 11, with a vertical centrally disposed web or fin 12, integral therewith and substantially dividing the interior of the jacket 10, or chamber, into two similar compartments, in this case, to form the opposed cylinders of my engine.

The rotor of my engine, comprises a substantially spool-shaped member, the flanges, 65 13, and 14 whereof form the respective heads, the arbor 15 of the rotor is suitably journaled through the web 12. A substantially wedge-shaped abutment 16, is radially disposed on the web 12, contacting the surface of the plates 13 and 14, which contact is uniformly secured by inserting yielding packings 17 at the apex of the wedge. A piston chamber, 18, protrudes outwardly from each respective flange of the rotor, 70 and in each cylinder is yieldingly pivoted a swinging piston 19, the outer contacting surface of which is also provided with suitable packing 20. Into the respective cylinders leads a fuel intake, 21, and leading 75 therefrom an exhaust port, 22, (see Fig. 1). At the top of the stationary casing and leading into each cylinder at a point substantially adjacent the abutments, 16, I lead a spark plug, 23, with suitable electrical 80 connections, not shown, but so timed as to spark when the parts are in a position as shown in Fig. 6.

From the foregoing it will be apparent that as soon as the pistons have passed the 90 intake port, the combustion chamber formed between the abutment 16 and the pistons, the surfaces of the pistons forming abutments, and ignition of the gas taking place at this point, the pressure will be applied 95 against the pistons, thus revolving the rotor. The exhaust port is positioned at substantially 45 degrees from the intake, so that the burnt gases are driven forward of the rotating swinging pistons, 19, and 100 forced out from the compartment.

Wherein I have shown and described my invention for use in connection with an explosive gas, I wish it understood that the same principle may be advantageously embodied in a motor employing steam as a motive power.

What I claim is:—

1. A rotary engine comprising a cylindrical compartment having intake and exhaust ports, a flanged rotor journaled to rotate therein, the flanges of said rotor

forming the cylinder heads, opposed compartments, one on the outer face of each flange, a swinging piston pivoted in each compartment, and a partition integral with 5 said cylindrical compartment and having an abutment thereon engaged by said swinging pistons.

2. A rotary engine comprising a cylindrical compartment, a centrally disposed 10 web having a radial abutment thereon, said web dividing the compartment into two similar apartments, each apartment being provided with an inlet and exhaust port,

a spool-shaped rotor journaled in the web, and a swinging piston pivoted on each 15 flange of said rotor, the flanges of said rotor forming the heads of the respective cylinders.

In testimony that I claim the foregoing as my own I have hereto affixed my signature in the presence of two subscribing witnesses.

MARTIN BETZLE.
